CLAIM

The ornamental design for a wafer crystal domino, as shown and described.

DESCRIPTION

FIG. 1 is an exploded perspective of a wafer crystal domino according to the preferred embodiment of the present invention;

FIG. 2 is an end view of a wafer crystal domino according to the preferred embodiment of the present invention;

FIG. 3 is a side view of a wafer crystal domino according to the preferred embodiment of the present invention;

FIG. 4 is a rear view of a wafer crystal domino according to the preferred embodiment of the present invention; and,

FIG. 5 is an overhead view of a wafer crystal domino according to the preferred embodiment of the present invention.

The broken line showing of the dots is for illustrative purposes only, and forms no part of the claimed design.
